UNITED STATES PATENT OFFICE.

HARRY H. STYLL, OF SOUTHBRIIDGE, MASSACHUSETTS.

OPHTHALMIC MOUNTING.

Application filed March 12, 1920. Serial No. 365,184.

To all whom it may concern:

Be it known that I, HARRY H. STYLL, a citizen of the United States, residing at Southbridge, in the county of Worcester and State of Massachusetts, have invented certain new and useful Improvements in Ophthalmic Mountings, of which the following is a specification.

This invention relates to improvements in ophthalmic mountings and has particular reference to that type of mounting commonly known as a finger-piece, in which the mounting is retained on the face by pivoted spring actuated guard arms or the like.

15 The principal object of the present invention is the provision of a novel and improved construction of mounting in which the parts may be readily constructed and in which their ease of assemblage and of operation will be facilitated, and which will consequently commend itself on account of these advantages both to the manufacturer and to the consumer.

20 A further object of the present invention is the provision of a construction of this character which may if desired be so constructed as to reduce to a minimum the use of solder in forming the mounting and thus the softening and drawing of its temper, 25 an objectionable feature hitherto presented by mountings of this type in the past.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of the invention.

Figure I represents a front elevation of a mounting embodying my improvements.

Figure II represents a fragmentary sectional view of one form thereof.

Figure III represents a similar view with the parts in disassembled relation.

Figure IV represents a sectional view of another modification.

50 Figure V represents a similar view illustrating a slightly different form thereof.

Figure VI illustrates a slight variation of the structure shown in Figure V.

In the drawings, the numeral 1 designates the lenses which are suitably connected as by the lens attachments 2 to the ends of

the bridge or lens connecting member 3. This member 3 is connected at each end adjacent the lens attachment with a seat portion 4 for the guard lever 5 bearing at its forward end the finger-piece or actuating portion 6 and at its rearward end the guard 7 for engagement with the nose to retain the mounting in position on the face.

In that form of the invention illustrated in Figure II for example, I have shown as secured within the seat 4 and projecting upward thereabove the tube 8, while slidably engaged upon the tube 8 is the loose sleeve 9 having the outwardly extending peripheral flange 10 providing a spacing member. The lever 5 is rotatably mounted upon the lower end of the sleeve beneath the spacing member or flange 10 which extends laterally over the lever so as to engage the latter and prevent any rocking or tilting movement on the pivot while permitting of its free rotation.

Similarly the portion of the sleeve projecting above the flange serves to center the actuating spring 11 which is retained in position as is the sleeve 9 itself by the head of the screw 12, which is screwed into the sleeve 8.

In Figure III, I have shown a slight modification of the just described construction in which the sleeve 9 is further provided with the outwardly extending flange 13 at its upper end serving to hold the spring 11 in place thereon as a unitary structure so that the member 9 with the spring is a unit separate from the lever but capable of ready insertion within the aperture of the lever when the whole may as a unit be slipped into position on the rigid post member 8 carried by the bridge seat, thus facilitating assembling of the parts which may be subsequently locked in place by the screw 12.

A further advantage of this construction is that should the bearing become at all worn or the spring itself wear out, the screw 12 may be removed and the part 9 and spring be removed, leaving the lever in place on the mounting, and a new spring and centering and bearing member substituted and again secured in position.

A further development is illustrated in connection with Figure IV, in which in place of the single sleeve member 9 there is a lower tubular sleeve or washer member 14 fitting within and forming a bearing for the lever 5, while separate from but mounted on

the member 14 is a second flanged or spun tube 15 which carries the spring 11 as a unit therewith and serves as a spacing member fitting between the member 14 and the head 5 of the screw so that as the screw is tightened against the member 15 the member 14 will be pressed down toward the member 4 to better support and hold the member 5 against tilting movement.

- 10 If preferred, in place of making use of the separate fastening member 12 and the tube 8 to receive the member 12, I may form the post 16 on or secured to the bridge seat with a threaded upper portion 17, as shown 15 in Fig. V and if desired a reduced end 18, while the tube 9, is provided with an interior thread as at 19 at its upper end for engagement with the thread 17 of the post having the recesses 20 to receive the prongs 20 21 of a spanner which may thus be easily engaged with the member 9 to secure it in position. This spanner may if desired be subsequently employed to secure in position the retaining nut 20' engaged on the reduced 25 upper end 18 of the post and also locked by the spanner. As an alternative to this construction if desired to dispense with the locking nut, I may secure the post in the bridge seat, as shown in Figure VI, by 30 threading thereinto its lower end and spinning it over as at 22, and may form the tube or member 9' with the upper or top flange 13' similar to the member shown in Figure III, with the exception that the tube is here 35 interiorly threaded at its upper end so that it may be screwed onto the post by a spanner, thus at the one time providing a bearing member and a spring bearing recess, the member being locked by slightly heading or 40 spinning over the upper end of the post. I have here provided a structure which may be readily assembled, in that the post is rigidly held or supported by the bridge and the lever and tubular member may both be 45 slipped onto the post, the tubular member

being threaded to finally lock it in position, said tubular member carrying the necessary spring for actuation of the guard lever. This form of mounting eliminates all possibility of loss or dropping of the parts during the assembling operation due to the rigid receiving post on the bridge and the fact that the lever and tubular member may both be slipped over the post while the parts may be readily locked through turning of 50 the tubular member as it approaches its final position.

I claim:

1. A mounting of the character described comprising a bridge having a post rising 60 therefrom provided with threaded ends, a guard lever and a securing device for the guard lever having a bearing portion encircling the post and projecting through the guard lever, having a steady portion laterally engaging the lever and an upwardly projecting spring receiving portion, said spring receiving portion being interiorly threaded to lockingly engage the post.

2. A mounting of the character described 70 comprising a bridge having a post rising therefrom provided with threaded ends, a guard lever and a securing device for the guard lever having a bearing portion encircling the post and projecting through the 75 guard lever, having a steady portion laterally engaging the lever and an upwardly projecting spring receiving portion, said spring receiving portion being interiorly threaded to lockingly engage the post, and a lock nut member engaged on the post above the securing device to further secure the parts in position.

In testimony whereof I have affixed my signature, in presence of two witnesses.

HARRY H. STYLL.
